UNITED STATES PATENT OFFICE.

ALBERT E. BAILEY, OF NASHUA, NEW HAMPSHIRE.

CONVEYER SYSTEM.

Application filed November 5, 1921. Serial No. 518,019.

To all whom it may concern:

Be it known that I, ALBERT E. BAILEY, a citizen of the United States, residing at Nashua, in the county of Hillsborough and 5 State of New Hampshire, have invented certain new and useful Improvements in Conveyer Systems, of which the following is a specification.

This invention relates to conveyer systems 10 and is especially concerned with the separation in a predetermined manner of the articles (hereinafter referred to as "carriers") which are handled by the system. It is the chief object of the invention to devise a 15 mechanism for automatically performing the operation of switching or diverting certain carriers into one path and certain other carriers into another path.

The nature of the invention will be readily understood from the following description 20 when read in connection with the accompanying drawings, and the novel features will be particularly pointed out in the appended claims.

25 Referring now to the drawings,

Figure 1 is a plan view of a portion of a conveyer system including a switching or diverting mechanism embodying the present invention; and

30 Fig. 2 is a side elevation of the construction shown in Fig. 1.

The construction shown comprises a conveyer belt 2 travelling from right to left, as indicated by the arrows, Fig. 2, and supported on a series of rollers 3 mounted in a suitable frame work. This conveyer transports carriers of different sizes, the carriers shown in the drawings consisting of relatively small boxes A and larger boxes B. 35 The frame work supporting the rollers comprises angle irons 4-4, the upright flanges of which guide the boxes laterally as they are carried along by the belt. At one side of the conveyer this upright flange is cut away for a short distance and a short spiral chute 6 leads from the conveyer at this point and runs to a lower conveyer belt 7, located immediately under the conveyer 2 but travelling in the opposite direction.

40 In the present instance it is desired to divert or switch the small boxes or carriers A off the upper conveyer into the chute 6 so that they will be delivered to the lower belt

7 and carried to another part of the building.

For this purpose a novel switch mechanism is provided which comprises a switch arm 8 of relatively stiff construction, as best shown in Fig. 1, which is secured at one end to an upright support 9 that is pivoted at both its upper and lower ends. This enables the switch arm to swing back and forth across the belt 2. Normally this switch arm is held in its operative position, substantially as shown in Fig. 1, by means of a weight 10 which is connected by a cord or chain 11 with a post 12 secured to the outer or free end of the arm 8, the cord or chain running over a pulley supported in the upper part of a standard 14.

It will be observed that if this switch arm remained constantly in the position in which it is shown in Fig. 1, it would divert all the carriers off the conveyer unit 2 into the chute 6. It is desirable to divert only the small carriers A, and in order to prevent this mechanism from diverting the other carriers also, a mechanism is employed which enables the larger carriers to move the switch into an inoperative position.

This mechanism comprises an operating arm 15 which is secured to an upright member 16 pivoted at its upper and lower ends so that this arm, like the switch arm 8, can swing back and forth in a horizontal plane 35 across the belt 2. This arm is located at such an elevation, however, that the small carriers A pass under it, but the large carriers B strike it.

The outer end of the arm 15 lies just 90 behind an upright bar 12 which is secured to the outer end of the arm 8, so that the weight 10 normally holds both the arms 8 and 15 in the positions shown in Fig. 1, or slightly beyond these positions; that is, completely across the belt 2. Consequently, so long as the carriers brought to the switch mechanism are small enough to pass under the operating arm 15, they will be caught by the arm 8 and diverted into the chute 6 which will deliver them to the lower belt 7. When a large carrier B, however, strikes the operating arm 15 it swings this arm about its pivot into a position substantially parallel with the conveyer belt, this arm operating through its connection 12 with

the switch arm 8 to carry the switch arm into a position beside the path of travel of the carriers and therefore into such a relationship that it is inoperative to switch 5 these carriers into the chute 6. In other words, the large carriers travel uninterruptedly along the belt 2. As soon as one of the large carriers B has passed the switching mechanism, the weight 10 will return 10 both the switch arm 8 and the operating arm 15 to their normal or operative positions.

It will now be understood that this invention provides a very simple mechanism 15 for automatically separating large from small carriers, that this mechanism operates entirely automatically, and that due to the nature of its construction it is subject to only very slow depreciation and will require 20 attention at only very infrequent intervals.

While I have herein shown and described the best embodiment of the invention of 25 which I am at present aware, it will be understood that this embodiment may be modified without departing from the spirit or scope of this invention.

What is claimed as new is:

1. In a conveyer system, the combination 30 of a conveyer unit for handling carriers of different sizes, and mechanism for automatically switching the small carriers off said conveyer unit while permitting the large carriers to travel along said unit.

2. In a conveyer system, the combination 35 of a conveyer unit, a switch movable across the path of travel of the carriers transported by said conveyer from a position in which it is operative to divert said carriers to a 40 position inoperative for said purpose, and mechanical means arranged to be operated by certain of said carriers for moving said switch across said path from one of said positions to another.

3. In a conveyer system, the combination 45 of a conveyer unit for transporting carriers of different sizes, a switch arm normally positioned to divert small carriers of said conveyer unit, and means whereby a large 50 carrier is enabled to move said arm automatically into a position inoperative for said purpose.

4. In a conveyer system, the combination 55 of a conveyer unit, a switch movable across the path of travel of the carriers transported by said conveyer from a position in which it is operative to divert said carriers to a position inoperative for said purpose, and mechanical means arranged to be op-

erated by carriers of certain dimensions for 60 moving said switch across said path from one of said positions to another.

5. In a conveyer system, the combination 65 of a conveyer unit, a switch movable across the path of travel of the carriers transported by said conveyer from a position in which it is operative to divert said carriers to a position inoperative for said purpose, and a movably mounted operating arm arranged to be moved by the contact therewith of certain of said carriers, said arm being connected with said switch to move the switch from one of said positions to another.

6. In a conveyer system, the combination 75 of a conveyer unit, a switch movable across the path of travel of the carriers transported by said conveyer from a position in which it is operative to divert said carriers to a position inoperative for said purpose, 80 and a movably mounted operating arm arranged to be moved by the contact therewith of certain of said carriers, said arm being connected with said switch to move the switch from one of said positions to another, and means for holding said arm 85 and switch normally in predetermined positions.

7. In a conveyer system, the combination 90 of a conveyer unit for transporting carriers of different sizes, a switch arm, a pivoted operating arm, and means for yieldingly holding said arms in a diagonal position across the path of movement of said carriers with the operating arm in the path of 95 travel of the larger carriers only, said arms being connected to enable the operating arm to move the switch arm into an inoperative position when the operating arm is struck by a large carrier.

8. In a conveyer system, the combination 100 of a conveyer belt, a chute diverging from said belt, a pivotally mounted switch arm normally positioned diagonally across said belt to divert carriers conveyed by the belt into said chute, a pivotally mounted operating arm normally positioned across the path 105 of travel of large carriers conveyed by said belt, said arms being connected to enable the operating arm to move the switch arm into an inoperative position when the operating arm is moved by a large carrier, and a weight connected with said arms and operative to return them to their normal positions after they have been moved out of 110 said positions by one of the large carriers.

ALBERT ELIE BAILEY.
